Primary Examiner—Janice E. Seeger*Assistant Examiner*—Zenia I. Bennett(74) *Attorney, Agent, or Firm*—Boyle Fredrickson, S.C.(57) **CLAIM**

The ornamental design for a desk, as shown and described.

DESCRIPTION

FIG. 1 is an isometric view of a desk incorporating my new design, wherein the phantom areas of the legs represent indeterminate length and wherein the remaining portions shown in phantom form no part of the claimed design;

FIG. 2 is a front elevation view thereof;

FIG. 3 is a left side elevation view thereof, the right side elevation view being a mirror image;

FIG. 4 is a rear elevation view thereof;

FIG. 5 is a top plan view thereof;

FIG. 6 is a bottom plan view thereof;

FIG. 7 is an isometric view showing a second embodiment of a desk incorporating my new design, in which the side elevation views are the same as shown and described with respect to FIG. 3;

FIG. 8 is a front elevation view thereof;

FIG. 9 is a rear elevation view thereof;

FIG. 10 is a top plan view thereof; and,

FIG. 11 is a bottom plan view thereof.
